UNITED STATES PATENT OFFICE

JAMES N. PRYOR, OF BALTIMORE, MARYLAND, ASSIGNOR TO WAY VEND CORPORATION,
OF BALTIMORE, MARYLAND, A CORPORATION OF MARYLAND

COIN-CONTROLLED APPARATUS

Application filed August 1, 1928, Serial No. 296,688. Renewed September 2, 1930.

This invention relates to improvements in coin controlled mechanism for vending machines. The invention relates more particularly to improvements in the coin guide for conducting coins from the entrance slot into the coin slide, whereby the coin guide is self-clearing; to improvements in the arrangement of a magnet for arresting magnetizable slugs, whereby such slugs are prevented from passing to the coin slide and are discharged from the guide; to improvements in the slot in the coin slide, whereby thin coins will be automatically discharged from the slot; to improvements in the connector between the coin slide and the article delivery slide; to improvements in means for making a predetermined division of the total number of coins entering the machine, and to other features, the details of which will be hereinafter pointed out.

In the accompanying drawing,

Fig. 1 is a right side elevation of the coin controlled mechanism;

Fig. 2 is a top plan view of the same;

Fig. 3 is a left side elevation of the same;

Fig. 4 is a section on the line 4—4 of Fig. 3;

Fig. 5 is a right side elevation of the coin chute, showing its movable side pushed inwardly from normal position, the front plate being shown in section;

Fig. 6 is a similar view, showing the left side of the coin chute;

Fig. 7 is a section on the line 7—7 of Fig. 3;

Fig. 8 is a section through the front plate and coin slide on the line 8—8 of Fig. 7; and,

Fig. 9 is a section the same as in Fig. 4, but showing the coin slide pushed rearwardly a short distance from its normal position.

Referring to the drawing, *a* represents a front plate, adapted to be attached to a suitable casing containing articles to be sold, this plate being provided in its upper part with a depression 1, in the bottom of which is a vertical coin slot 2, (Figs. 1 and 2). Below the coin slot, the plate is provided with an outwardly extending boss 3, having an annular depression 4, and in the center

of the boss is an opening 5 to receive a push rod 6. Four parallel rods 7, 8, 9 and 10 connect the front plate with a back plate *b*, the plates and rods constituting the frame upon which the various parts of the mechanism are carried. 55

An article delivery slide *c* extends through a horizontal slot in the back plate and the forward end of this slide has a downwardly turned flange 11, (Fig. 5) provided with an opening 12, through which a horizontal rod 13, secured to the front plate, extends. A spring 13' on this rod bears against the flange on the slide and constantly presses the slide forwardly, toward the front plate. This article delivery slide has an upwardly projecting stud 14, adapted to be engaged by a connecting lever *d*, which is mounted upon the coin slide *e*. 60 65

The coin slide *e* is made of sheet metal, 70 bent into U-form, comprising a top 15 and downwardly extending ends 16—17, these end pieces having guide openings through which the guide rods 7 and 8 extend. The push rod 6 is connected to the forward end piece 16, and a sheet metal foot 18, secured to the latter end piece, extends downwardly therefrom and has grooved guideways 18^a and 18^b which fit around the edges of the article delivery slide *c* and form a sliding 75 80 connection between the latter slide and the coin slide.

A relatively long spring 19 is interposed between the stationary back plate *b* of the frame and the front plate 16 of the coin slide, this spring, as shown, being coiled about an extension of the push rod 6 and extending into a tubular housing 20, which is secured to the plate *b*. This spring constantly presses the coin slide toward the front plate *a* and toward an upwardly projecting stop 21 on the forward end of the delivery slide. 85 90

In the top plate of the coin slide is a coin slot 22, slightly wider than the thickness 95 of the coin which is employed to operate the machine, and one end wall 22^a of the slot is inclined with respect to the plane of the slot, so that the slot is slightly longer at one side than at the other. As shown, 100

the wall 22^a is part of a lever 23 which is pivoted to a bracket 24 on the top plate of the coin slide. A spring 25 normally holds the lever so that this inclined part 22^a closes the end of the slot. An arm 23^a on the lever projects at one side of the coin slide and is adapted to engage a stop 26, fixed to the back plate *b*, when the slide approaches the inner limit of its movement, and this stop causes the lever to rock and thereby open the end of the coin slot to allow the coin to drop through the slot on to a downwardly inclined plate 27, which guides it laterally out of the mechanism and into a hopper *f*.

The connector *d* is pivoted at 28 to the rear side of the coin slide, and one of its arms extends over the top of the slide and has a feeling finger 29^a which is movable transversely of the slot, at its central portion. The other arm 29^b of the connector has a foot 29^c which is movable transversely of the delivery slide *c* into and out of line with the stop 14 thereon. A spring 30, which bears against the arm 29^b of the connector, constantly tends to press the finger 29^a into line with the coin slot 22 and the foot 29^c out of line with the stop 14. In the normal positions of the slides, a fixed cam plate *g* holds the connector in the position shown in Figs. 2 and 5. In this position, a coin of the proper size to operate the machine, inserted through the entrance slot 2 and passing through a coin chute *h*, can pass the finger of the connector and enter the slot 22 in the coin slide. If the coin or check is considerably thinner than the proper coin, it will drop out through the longer side of the slot; but if it is of normal thickness and diameter, it will remain in the slot. Upon moving the coin slide rearwardly a short distance, the depending arm of the connector will ride on to the inclined wall 31 of the cam plate *g* until the finger engages the side of the coin, when the coin will stop the swinging movement of the connector before the foot on its lower end rides out of line with the stop 14, on the article delivery slide. Continued inward movement of the coin slide will then, through the connector, cause the article delivery slide to move backward to eject one of the articles to be vended. Near the limit of the inward movement of the coin slide, the depending arm of the connector will engage the cam surface 32 of the cam plate and ride on to the part 33, thus causing the connector to move away from the side of the coin, and a slight further movement of the coin slide will cause the lever 23^a to engage the stop 26 and rock this lever to open the end of the coin slot and release the coin.

If a washer should enter the coin slot in the coin slide, it will be evident that the feeling finger of the connector will pass

through the hole in the washer when the depending arm of the connector passes on to the cam surface 31. As the cam surfaces 31 and 32 form a relatively deep notch in the cam bar *g*, the foot of the connector will move out of the path of the stop 14 as the coin slide moves rearwardly, and hence the delivery slide will not be operated by the coin slide and the washer will be retained on the finger until the connector is about to pass from the cam surface 32 on to the cam surface 33, when the finger will be withdrawn from the washer and the latter will then be released from the coin slot by the engagement of the lever 23 with the stop 26. Thus, the mechanism provides for detecting washers with the connector and for stripping them from the connector, and for preventing the operation of the delivery slide by the use of washers.

The coin chute or guide *h* is composed of two similar side walls 34 and 35, the former attached to the stationary front plate and the latter attached, by a foot-piece 35^a, to the top of the coin slide. A flange 35^b on the side 35 projects over the rear edge of the side 34 and forms the back wall of the guide. The rear edges of the side walls are partly semi-circular in outline, and the flange 35^b extends around this semi-circular part, terminating at a sufficient distance above the coin slide to permit coins to pass out of the guide. A flange 35^c, at the bottom of the side 35, projects under the side 34, and is inclined toward the coin receiving slot 22 in the coin slide. This flange forms a bottom for the guide and directs coins toward the slot. The side plate 34 of the coin guide is attached at its forward edge to a cross-piece 36 which is secured to the inner side of the front plate *a*, above the entrance slot 2. It is also attached to a shelf 37, the latter having a lateral extension 37^a which is secured to the front plate *a*. The shelf 37 fits into a notch in the side wall 34 of the coin guide and is soldered or brazed to said wall. This shelf is wedge-shaped and is adapted to fit into a correspondingly shaped notch 35^d in the side wall 35. When the coin slide is in its normal position, as shown in Figs. 1 and 2, the shelf, which is immediately below the coin entrance slot, forms a baffle in the coin guide, so that a coin passing from the entrance slot 2 to the coin receiving slot in the coin slide must take a tortuous course through the coin guide, and hence it is impractical to fish a coin out of the coin slide by inserting a wire, for instance, through the entrance slot.

When a coin of the proper size to operate the machine is inserted through the entrance slot into the coin guide, it will drop on to the shelf 37 and from thence pass to the flange 35^c, and thence to the slot in the coin slide. If paper or any substance is inserted into the coin guide which will not pass

through, when the slide is pressed rearwardly the side wall 35 of the coin slide will move rearwardly with the slide, and the paper or other substance obstructing the 5 guide will fall down between the front plate and the coin slide. Thus, the coin guide is self-clearing when foreign substances are inserted which would obstruct the passage-way through the guide. When the coin 10 slide is released it returns to normal position, carrying the side wall 35 into position parallel with the side wall 34.

In order to detect iron slugs which may be inserted in the machine, a permanent magnet *k* is provided, and the poles of this magnet normally extend through openings 38 in the side wall 34 of the coin chute. This magnet is mounted upon one end of a lever 39, which is pivoted at its other end upon a 20 stud 40, secured to the front plate. The lever 39 is thus adapted to swing laterally with respect to the plane of the coin chute. A spring 41 constantly presses the free end of the lever toward the coin chute and the 25 poles of the magnet are thus held within the openings 38 so that an iron slug passing through the coin chute will be arrested by the magnet when it comes opposite its pole pieces. A cam 42 on the lever 39 normally projects into the path of movement of the 30 forward end-pieces 16 of the coin slide. When the coin slide is pushed rearwardly, this end piece presses against the cam 42 and rocks the lever 39 laterally, as indicated in 35 dotted lines in Fig. 7, so as to withdraw the pole pieces of the magnet from the openings 38, and thus, if a slug has been arrested by the magnet, it will be stripped from the pole pieces of the magnet and will drop downward between the coin slide and the front plate *a*, the coin slide at this time being some distance inward from its normal position so that the slug cannot enter the slot in the slide. Upon the return of the slide to its 40 normal position, the spring 41 will rock the lever 39 toward the coin chute and the pole pieces of the magnet will again enter the openings 38 in the coin chute.

When the mechanism is operated by a 50 proper coin and an article has been delivered, the slot in the coin slide is opened, in the manner heretofore described, by engagement of the lever 23 with the stop 26, and the coin drops out of the slot 22. The 55 coin passes from the slot down the inclined plate 27 into the hopper *f*. It is desirable to make a division of the coins which pass through the machine, so that a certain proportion of the coins will flow into one receptacle and the remainder into another receptacle. This is in order that the owner of the machine who supplies the vended goods 60 may have his proportionate amount of the proceeds delivered into a receptacle, and the concessionaire may have his proportionate of

the proceeds delivered into a separate receptacle. For this purpose, two chutes 43 and 44 are connected to the lower end of the hopper and a valve 45 is provided at the junction of these chutes, for directing the coins into one chute or the other. The valve 45 normally closes the upper end of the chute 44, which leads to the receptacle (not shown) for the coins which go to the concessionaire. This valve is secured to a crank 46, and the 70 arm 46^a of the crank is pivotally connected to a rod 47 which extends upwardly adjacent the guide rod 9 of the coin controlled mechanism. The rod 47 has a curved end 47^a which extends partly around the axis of a stud 48, upon which is mounted a ratchet wheel 49, the stud being secured to the guide bar 9. A tripping pin 50, projecting from the ratchet wheel, engages the curved part of the rod 47 and is adapted to lift the rod 75 and thereby cause the valve 45 to swing into position to close the chute 43 and direct a coin into the chute 44, once in each revolution of the ratchet wheel. A gravity-operated pawl 51, pivoted to the forward end of 80 the delivery slide *c*, projects laterally from the slide into line with the teeth of the ratchet wheel, and hence each time the delivery slide is actuated to eject a vendable article, the ratchet wheel is turned the distance of one tooth. If the concessionaire's 85 proportion of the receipts is to be 20%, the ratchet wheel will have five teeth, as shown in the drawing, and as the ratchet wheel is turned, the tripping pin will rock the valve 90 45 once for every five articles sold, and hence one coin out of five will pass through the chute 44 and the other coins, four in number, will pass through the chute 43. 95

The article delivery slide is provided with 100 a short rack 52, adapted to engage a pawl 53 while the slide is moving rearwardly, this pawl being adapted to prevent the slide from moving forward until it has completed 105 its full rearward movement and ejected a package. These pawl and ratchet devices are in common use and form no part of the present invention. In order to prevent the insertion of a coin in the machine while the mechanism is being operated by a previously 110 inserted coin, I provide a shutter 54, in the form of a lever, which is pivotally mounted upon the guide rod 7. This lever extends upwardly from the guide rod in contact 115 with the rear of the front plate *a* and its upper end is guided by the cross-bar 36, the major portion of which is spaced from the front plate to provide a guide slot 36^a. The shutter has a horizontal arm 55, having a cam surface adapted to be engaged by the coin slide in the forward position of the latter, and the slide, in moving forward, 120 engages this arm and rocks the shutter away from the coin slot 2. A spring 56, bearing 125 on the arm 55, constantly tends to move the 130

shutter into position to close the slot. When the coin slide is moved rearwardly a slight distance, the shutter is moved by the spring to close the slot.

5 It is believed that the operation of the apparatus will be clear from the above, without further description.

What I claim is:—

10 1. In a coin controlled mechanism, a front plate having an entrance slot for coins, a slide having a coin receiving slot, and a coin guide for conducting coins from the former to the latter slot, one side wall of the guide being fixed to the front plate and the opposite side wall being fixed to the slide.

15 2. In a coin controlled mechanism, a front plate having an entrance slot for coins, a slide having a coin receiving slot, a coin guide for conducting coins from the former to the latter slot, one side wall of the guide being fixed to the front plate and the opposite side wall being movable with the slide, said latter wall having a notch in its forward edge, and a stationary shelf below the entrance slot, adapted to fit in said notch.

20 3. In a coin controlled mechanism, a coin slide having a coin slot, an article delivery slide having a stop, a stationary cam bar, a lever centrally pivoted to the slide and having one arm movable transversely of the coin slot and the other arm movable into and out of line with said stop, and a spring pressing said lever against the cam bar, said 25 cam bar having a part adapted to hold the lever out of line with the slot and line with said stop, in the normal position of the slide, and having another part adapted to permit the lever to rock first into line with the slot and out of line with the stop and then out of line with the slot and into line with the stop, when the slide is pushed rearwardly.

40 4. In a coin controlled mechanism, a front plate having an entrance slot for coins, a slide having a coin slot, a coin guide extending between said slots, one side of the coin guide being fixed to the front plate and the other being fixed to the slide, a magnet support movable toward and from the fixed 45 side of the coin guide, a magnet on the support having pole pieces projecting through said fixed side of the guide, a spring pressing said support toward the guide, and means for forcing said support away from 50 the guide when the slide is pushed rearwardly.

In testimony whereof I affix my signature.

JAMES N. PRYOR.
